QUICK CONNECT SINK MOUNTING FOR
GARBAGE GRINDERS

Charles Thierer, Belleville, N.J., assignor to National
Rubber Machinery Company, Akron, Ohio, a corpora-
tion of Ohio

Filed July 10, 1957, Ser. No. 671,085

4 Claims. (Cl. 241—100.5)

This invention relates generally, as indicated, to a quick-connect sink mounting for garbage grinders and the like whereby such equipment may be quickly and conveniently mounted in suspended condition underneath a kitchen sink.

Hitherto, a common form of sink mounting for garbage grinders has comprised an internally threaded upper tubular housing on the grinder that has threaded engagement with the sink flange that is inserted to extend downwardly through the sink drain opening. Said sink flange is usually provided with a radially outwardly extending flange at its upper end that overlies the margin of the sink drain opening. In such installation, it is also customary to provide a metal-backed sealing ring which is pressed up into sealing engagement under the sink as by means of jack screws having threading engagement in the upper end of the garbage grinder housing. As evident, the installation of such garbage grinder is a two-man operation, requiring one man to hold the garbage grinder and the other man to thread the sink flange into the garbage grinder housing. One man may make the installation, but, to do so, he must provide a box or like support on which the grinder rests while he screws in the sink flange. A typical sink mounting of the character referred to is illustrated in the patent of John Drew Pat. No. 2,657,397, granted under date of Nov. 3, 1953.

With the foregoing in mind, it is a primary object of this invention to provide a novel form of sink mounting for garbage grinders which can be easily and quickly accomplished as a one-man job without propping up of the grinder as above explained.

It is another object of this invention to provide a novel form of sink flange assembly which may be initially mounted on the sink, such assembly providing readily accessible bayonet-type mounting means which requires simply an upward lifting of the grinder and then a few degrees rotation thereof.

It is another object of this invention to provide a novel form of sink flange assembly from which the garbage grinder is hung and which includes a resilient packing ring between said assembly and grinder which functions, not only as a joint seal, but also as a cushioning means to minimize transmission of vibrations and grinding noises from the grinder to the sink proper.

It is another object of this invention to provide a quick-connect sink mounting in which the aforesaid packing ring additionally provides a resilient seat for the sink stopper, which stopper, in well known manner, may be employed to energize and de-energize the grinder motor while permitting flow of water through the sink drain opening and to seal the sink drain opening when the sink is to be used in its intended manner to hold water therein.

Other objects and advantages of the present invention will become apparent as the following description proceeds.

To the accomplishment of the foregoing and related ends, the invention, then, comprises the features herein-

2

after fully described and particularly pointed out in the claims, the following description and the annexed drawings setting forth in detail a certain illustrative embodiment of the invention, this being indicative, however, of but one of the various ways in which the principle of the invention may be employed.

In said annexed drawing:

Fig. 1 is a side elevation view showing a garbage grinder as installed through the expedient of the present quick-connect sink mounting;

Fig. 2 is a vertical cross-section view through the axis of the sink drain opening and of the upper portion of the garbage grinder housing, the garbage grinder being shown in its suspended position from the sink flange assembly; and

Fig. 3 is a top plan view of the mounting ring which constitutes an element of the sink flange assembly.

Referring first to Fig. 1, the reference character S denotes the bottom of a sink from which the garbage

grinder 1 is suspended, said garbage grinder, as well-known in the art, comprising a tubular upper housing 2 which provides a refuse-receiving chamber 3 therewithin. Extending across the lower end of said chamber 3 is a rotary impeller 4 that is operative, in cooperation with a surrounding, internally grooved shredder ring 5 to comminute refuse thus introduced into the grinding chamber 3, said impeller 4 being keyed on the drive shaft 6 of electric motor 7. The motor housing 8 is hung from the bottom of the upper housing 2 as by means of a screw-actuated split clamp 9. The motor housing 8 is formed with a discharge port 10 through which, by way of conventional pipe fittings and trap, the comminuted refuse is conducted into the sewer with the assistance of water that flows from the sink S into the garbage grinder 1 during the grinding operation.

Said upper housing 2 is provided with a port 11 to which the drain hose of a dish-washing machine is adapted to be connected, and said upper housing usually has mounted thereon a switch box 12, provided with a manually operated on-off switch 14. In series with switch 14 is a control switch 15, that is designed to be actuated by means of the radially movable plunger 16 (see Fig. 2) which has its inner end extending into the housing.

A full disclosure of the garbage grinder of the type just described, including the control cover 17 for actuating the aforesaid plunger 16 will be found in the aforesaid Drew patent. Thus, when said control cover 17 is turned so as to move the plunger 16 outward, the control switch 15, in conjunction with the manual switch 14, which is normally left in "on" position, will energize the grinder motor 7.

In the present case, the quick-connect sink mounting comprises a sink flange assembly including a sink flange 20 that has a radially outwardly extending flange 21 that overlies the margin of the sink drain opening 23. The portion of the sink flange 20 which extends downwardly through the sink drain opening is formed with a peripheral groove in which is disposed a retainer ring 24 (preferably in the form of a snap ring), which serves to support the mounting ring 25. Said mounting ring 25 and the metal-backed sealing ring 26—27, are first slipped over the sink flange 20 before said snap ring 24 is thus installed.

By turning the several jack screws 28 that are threaded into said mounting ring 25, the metal-backed sealing ring 26—27 is pressed upwardly into firm, sealing engagement under the marginal portion of the sink drain opening 23, the snap ring 24 serving to provide an abutment shoulder for exerting such clamping pressure. Thus, the flange 21 of said sink flange 20 is drawn down tightly against the margin of the sink drain opening. If desired, and is the customary practice, a paste or calk-like

material may be applied around the sink drain opening, whereby a water-tight seal is established in that region. Of course, the rubber ring 27 also is arranged for deformation so as to establish water-tight joint with the sink S.

As best shown in Fig. 3, said mounting ring 25 is formed with a circular series of keyhole slots 29, herein three in number, the wide portions 30 of such slots being larger than the heads 31 of the hanger screws 32 that are threaded into the upper end of the garbage grinder housing 2. The garbage grinder housing 2 is counterbored to receive the rubber-like packing ring 34. The narrow portions 35 of said keyhole slots 29 which intersect the wider portions are of such size as to accommodate the shanks of said screws 32 but smaller than the heads 31 thereof.

From the foregoing, it is clear that with the headed hanger screws 32 unscrewed somewhat from the position shown in Fig. 2, the garbage grinder 1 is installed simply and quickly by raising the same until the heads 31 of said screws 32 pass through the wide portions 30 of the keyhole slots 29 whereupon just a few degrees rotation (10°) of the grinder 1 is required to position the heads 31 over the narrow portions 35 of said keyhole slots. Thereafter, as the hanger screws 32 are tightened, the flange 36 of the packing ring 34 is deformed between the mounting ring 25 and the upper end of the garbage grinder housing 2, and the lower edge of the sink flange 20 extends into an annular recess formed in said packing ring to form a resilient annular seat 37 with which the frusto-conical seat of the control cover 17 makes sealed engagement more readily than it would with the metal seat ordinarily provided on the sink flange 20.

As previously mentioned, said resilient packing ring 34 has a many-fold function, namely, to establish a fluid-tight joint between the sink flange assembly and the garbage grinder 1, to provide a resilient seat 37 for the garbage grinder control cover 17, and to provide a resilient joint between the grinder 1 and the sink flange assembly so as to minimize the transmission of vibration and grinding noises to the sink S.

The mounting ring 25 aforesaid, may be fabricated from sheet stock, steel or bronze, for example, and preferably is formed with a peripheral reinforcing flange 38 to prevent development of waviness therein by the forces applied at circumferentially spaced regions by the jack screws 28 and by the hanger screws 32.

While the present invention as herein disclosed contemplates the provision of the keyhole slots 29 in mounting ring 25 and hanger screws 32 screwed in the grinder housing 2, it is to be understood that, if desired, the screws 32 may be screwed upwardly into ring 25 with their heads 31 at the bottom and the keyhole slots 29 may be formed in a flange at the upper end of housing 2.

Other modes of applying the principle of the invention may be employed, change being made as regards the details described, provided the features stated in any of the following claims, or the equivalent of such, be employed.

I therefore particularly point out and distinctly claim as my invention:

1. Garbage grinder suspension means comprising a sink flange adapted to be inserted through a sink drain opening with its top flange overlying the margin of such opening; said sink flange adjacent its lower end having a grinder mounting ring engaged with a shoulder of said sink flange; a sealing ring disposed to underlie the margin of such opening; screw means bearing on said mounting ring to press said sealing ring up against the margin of such opening and to draw the top flange down against the margin of such opening; said mounting ring being formed with a series of circumferentially extending key-

hole slots for supporting a garbage grinder; and a corresponding series of headed screw members extending upwardly from the grinder to pass upwardly through the wide portions of such slots and to overlie the narrow portions of such slots when the grinder is lifted and the screw heads circumferentially so positioned.

2. Garbage grinder suspension means comprising a sink flange adapted to be inserted through a sink drain opening with its top flange overlying the margin of such opening; said sink flange adjacent its lower end having a grinder mounting ring engaged with a shoulder of said sink flange; a sealing ring disposed to underlie the margin of such opening; screw means bearing on said mounting ring to press said sealing ring up against the margin of such opening and to draw the top flange down against the margin of such opening; a garbage grinder suspended from said mounting ring by means of interengaging elements on said mounting ring and said grinder; said interengaging elements comprising a series of circumferentially extending keyhole slots in said mounting ring and headed screw members in threaded engagement with said grinder of which the heads pass through the wide portions of the slots when the grinder is lifted and radially overlie the narrow portions of the slots when the grinder is rotated a part turn; and a resilient ring interposed between said grinder and said mounting ring, said headed screw members, when tightened, being effective to clamp said resilient ring between said mounting ring and said grinder.

3. Garbage grinder suspension means comprising a sink flange adapted to be inserted through a sink drain opening with its top flange overlying the margin of such opening; said sink flange adjacent its lower end seating a grinder mounting ring; a sealing ring disposed to underlie the margin of such opening; screw means bearing on said mounting ring to press said sealing ring up against the margin of such opening and to draw the top flange down against the margin of such opening; said mounting ring being formed with a series of circumferentially extending keyhole slots for supporting a garbage grinder; a corresponding series of headed screw members extending upwardly from the grinder to pass upwardly through the wide portions of such slots and to overlie the narrow portions of such slots when the grinder is lifted and the screw heads circumferentially so positioned; and a resilient ring interposed between said grinder and said sink flange and adapted to be compressively clamped when said headed screw members are tightened.

4. Garbage grinder suspension means comprising a sink flange adapted to be inserted through a sink drain opening; said sink flange adjacent its lower end seating a grinder mounting ring; sealing means disposed to underlie the margin of such opening; and jack means bearing on said mounting ring to force said sealing means against the margin of such opening and to draw the top flange down against the margin of such opening; said mounting ring being formed with a series of circumferentially extending keyhole slots for supporting a garbage grinder; a corresponding series of headed screw members extending upwardly from the grinder to pass upwardly through the wide portions of such slots and to overlie the narrow portions of such slots when the grinder is lifted and the screw heads are circumferentially so positioned; and a resilient ring interposed between said grinder and said sink flange and adapted to be compressively clamped when said headed screw members are tightened.
